STANCHION

Roy F. Harding, Charlo, Mont.

Application January 28, 1948, Serial No. 4,913

7 Claims. (Cl. 119—147)

1

The present invention relates to certain new and useful improvements in stall stanchions such as are commonly used to temporarily restrain milch cows in present day milking parlors.

Broadly, the invention at bar has to do with a stanchion which embodies vertical stiles, one of which is fixed and the other one of which is pivotally and adjustably mounted and adapted to swing away from the fixed member to space the members apart and to thus open the stanchion.

More particularly, novelty is thought to reside in an ingenious arrangement of primary and secondary latches and a remotely controlled pull rope for operating same from a point adjacent the rear end of the animal in a manner to save the milker steps and to considerably expedite opening and closing the stanchion.

In reducing to practice the preferred embodiment of the invention, an arrangement of latches is provided whereby, through the medium of a novel actuating lever, the rope is pulled once to readily release the primary latch to permit the stanchion to open and when pulled upon the second time serves, by way of appropriate construction means, to act upon the latches to allow the stanchion to close and to be retained in closed position.

Other objects and advantages will become more readily apparent from the following description of the accompanying illustrative drawings.

In the drawings:

Figure 1 is a perspective view illustrating a stanchion and a latch and latch controlling means constructed in accordance with the present invention, the stanchion being shown closed.

Figure 2 is a fragmentary elevational view of the structure and assemblage seen in Figure 1, and

Figure 3 is a fragmentary top plan view.

Briefly summarized, the invention has to do, on the one hand, with a stanchion which is characterized by a fixed vertical stile on one side, a hingedly mounted complementary vertical stile on the other side opposed to the fixed stile, and having spring means to normally swing said pivoted stile to stanchion-opening position. A primary gravity-lowered latch bridges a space between the upper ends of the stiles and is hinged adjacent to the fixed stile and has a detent on its free end releasably engageable with the upper end of the movable stile. Remote controlled means, including a balanced lever is provided. The lever has a roller-equipped return limb for the pivoted or swingable stanchion stile and said lever carries a self-resetting vertical secondary

2

latch which coacts with a lifting finger on the primary latch, all in the manner to be hereinafter described.

Referring now to the drawings by distinguishing reference characters the stanchion, as a unitary structural assemblage, is denoted by the numeral 5 and comprises an angle iron or equivalent base member 6 which is suitably supported and which provides a foundation for a stationary stanchion stile 7, this being fixedly connected with the horizontal frame member 8. The movable stile or member is denoted by the numeral 9 and this is hingedly and adjustably mounted in the angle iron 6, as at 10. The numeral 11 designates a pull spring which serves to normally swing the stile 9 in a direction from left to right. Both stiles 7 and 9 are channel-shaped in cross sectional form.

The primary latch is horizontally disposed and denoted by the numeral 12 and this is pivoted as at 13 on a bracket 14 which is fixed to the frame members 8. The bracket includes a step-like element 15 which constitutes a rest upon which the latch 12 sits when it is in its downmost latching position, the position shown in the drawings. The detent portion of the latch, at 16 is a common type of nose construction and this is releasably latched to the upper end of the stile 9 and is fashioned into a cam surface 17 and is also formed with an extension providing a latch lifting stile releasing finger 18.

I next call attention to a horizontal relatively stationary fixed stall pipe or equivalent supporting member 19 which carries a fixture 20 having a depending ear 21. This ear serves to accommodate an adapter block 22 which is pivotally mounted on said ear, as at 23. The adapter block serves as a cradling mount holder for an L-shaped rope controlled actuator lever 24. This lever embodies a long horizontal arm 25 and a short inclined complementary limb 26 having a yoke provided with a rubber tired cushioning and stop roller 27. In practice, the lever 24 is scientifically and dynamically balanced for sensitive actuation. Adjustably mounted on the outer end for purposes of changing leverage as desired is a collar 28 to accommodate a pull rope or cable 29. The latter is trained over a pulley 30 and a second pulley 31 and terminates in a hand grip or knob 32. The latter is preferably arranged at the outer end of the stall (not shown), that is, adjacent the rear of the cow to permit same to be conveniently handled from that point.

Reference is had now to the so-called secondary or trip latch. The latter is denoted by the

numeral 33 and is pivoted midway of its upper and lower ends, as at 34, on a sleeve-type block 35. The latter is fitted and secured on the long limb 25 and has an outstanding member 35a constituting a stop. The latter occupies a position between the adapter block 22 and the upper end portion of said latch 33 and functions to keep the latter in its normal vertical position at right angles to the primary latch 12. A coiled spring 36 is provided and this is attached at one end to the upper end portion of the latch and is anchored on a lug 37 on the block 22. The lower end of the latch 33 is provided with a detent 38 for the finger 18 and is also provided with a self-re-setting cam surface 39.

The operation of the stanchion is briefly as follows: In the drawings we see the stanchion closed up. At this time the detent 16 on the latch 12 is seated against the upper closed end of the channel of the movable stanchion stile 9 and the latter takes the position shown in the drawings, which is the closed position. It is obvious that by lifting the latch 12 and disengaging the detent 16 the stile 9 will automatically swing from left to right on its pivot 10 in Figure 1 under the stress of the spring 11. To accomplish this the L-shaped actuating lever 24 is provided. Consequently, the user simply grasps the knob 32 and pulls on the rope 29 and this transmits the lifting action to the left hand end portion of the lever 24. The limb 25 now swings up on the anchoring pivot 23. Since the secondary latch 33 is carried by this limb it also travels up and serves to lift and disengage the detent 16 from the stile 9 permitting the latter to open. Said stile 9 swings open and comes into resting contact with the rubber cushioned wheel 27. Latch 33 is still engaged, during the opening phase of operation, with latch 12.

Now, to close the stile, the same rope is pulled in the same way, after having been released, of course, after the stated stanchion opening phase. Inasmuch as the limb 26 and its roller means is in direct contact and must push the stile 9 bodily, it will be necessary to give a strong pull, this time, on the knob. In so doing the stile 9 is pushed from right to left and as the limb 25 is pushed up its carries the detent 38 on the latch 33 up sufficiently high that it will now be disengaged from the latch 12. The latch 12 will now drop down by gravity and as the upper free end of the stile 9 swings toward it, it will strike the cam 17, lift up the latch and the latch will then drop by gravity and again lock 9 in place. When the rope is again released the limb 25 will drop down to its normal balanced horizontal position and in so doing the cam 39 will come into rubbing or wiping contact with the finger 18, which will allow the latch 33 to swing counter-clockwise, after which it will reengage beneath the finger 18 and the parts will be again set and readied to repeat the above-mentioned "opening phase."

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

Having described the invention, what is claimed as new is:

1. In a structure of the class described, a stationary support, fixture means rigidly mounted on said support, a counterbalanced self-righting L-shaped lever pivotally mounted for swinging on said fixture means, a pull cord adjustably connected to said lever, a cushioned roller mounted on said lever, a stationary frame member, a primary gravity actuated pivotally mounted latch on said frame member and having a detent, and a secondary latch pivotally mounted on said L-shaped lever and having a detent releasably engageable with said primary latch.

2. In a structure of the class described, a frame member, a bracket fastened on said frame member, said bracket having a latch abutting and seating check, a primary gravity lowerable latch pivotally mounted at one end on said bracket and normally resting on said seating check, the opposite end of said latch having a cam surfaced detent and a terminal extension projecting beyond said detent and constituting a lifting finger for a secondary latch, a stationary support member on a plane above said frame member, a remote cord controlled trip lever pivotally mounted on said support member, a secondary trip latch pivotally mounted on said lever and disposed at right angles to said primary latch and having a cam-edged detent releasably engaged with said lifting finger, and a spring anchored at one end to said lever and at its opposite end to said secondary latch.

3. In a structure of the class described, a frame member, a bracket fastened on said frame member, said bracket having a latch abutting and seating check, a primary gravity lowerable latch pivotally mounted at one end on said bracket and normally resting on said seating check, the opposite end of said latch having a cam surfaced detent and a terminal extension constituting a lifting finger for a secondary latch, a horizontal stationary support member on a plane above said frame member, a remote cord controlled trip lever pivotally mounted on said support member, a secondary trip latch pivotally mounted on said lever and disposed at right angles to said primary latch and having a cam-edged detent releasably engaged with said lifting finger, a spring anchored at one end to said lever and at its opposite end to said secondary latch, and an abutment mounted on and carried by said lever and constituting a stop and engageable with an adjacent edge portion of said secondary trip latch to maintain the latch normally in a vertical position and to permit the latch to swing freely in a direction away from the stop during the time the detent thereon reengages itself with said lifting finger.

4. The structure specified in claim 2, said lever being L-shaped and including a horizontally disposable long arm and a vertically disposable short arm, said long arm being in a plane with said support member when in its normal position, and a freely turnable roller mounted on said short arm.

5. In a structure of the class described, a remote control structure for coaction with a stanchion which includes a vertically disposed fixed stile, a vertically disposed and opposed swingable stile and a primary gravity latch bridging and normally holding the swingable stile in closed relation to the fixed stile; comprising a stationary horizontal pipe, a fixture rigidly mounted on and extending at right angles from said pipe, an adapter block hingedly mounted on said fixture,

an L-shaped lever including a long arm and a short arm, said long arm being fixedly mounted on said adapter block and being normally in a horizontal plane with said pipe, said short arm depending below said pipe and terminating in a yoke, a roller freely mounted for rotation in said yoke, a secondary trip latch pivoted intermediate its ends to the long arm, one end of said secondary latch extending at right angles and depending below said long arm and terminating in a cam edged detent, the other end of said latch extending at right angles above said long arm, a stop on said lever engageable with the last named end of the latch to maintain same at approximate right angles to said long arm, and a coiled spring anchored at one end on said adapter block and attached at its opposite end to that end portion of said trip latch situated above the pivotal mounting of said trip latch.

6. A remote controlled latch construction of the class shown and described, comprising, in combination, a stationary frame member, a pivoted vertical member, a gravity-lowered primary latch pivoted on said frame member and having a detent releasably engageable with said pivoted member, said detent having a cam surface and a complemental outstanding lifting finger, a counterbalanced self-righting L-shaped pivotally mounted lever, a manually actuatable remote control pull cord connected to and for operating said lever, a secondary trip latch at right angles to said primary latch and pivotally mounted on said lever and having a detent releasably engageable with said lifting finger, said L-shaped lever embodying a depending limb opposite to said piv-

oted member and said limb having a cushioned combined check and thrust return roller releasably engageable with said member.

7. Remote controlled latching and closing means for the pivoted vertical stile of a stanchion construction comprising a stationary horizontally disposed pipe, a fixture rigidly mounted on said pipe, an L-shaped lever including a normally horizontal long arm and a substantially vertical depending short arm, said long arm being hingedly mounted on said fixture, said short arm having a free end portion provided with a freely rotatable roller, a secondary trip latch pivoted intermediate its ends on said long arm, fixed stop means on said long arm, said latch being normally engaged with said stop means and thus disposed at right angles to the longitudinal axis of said long arm, and spring means connected with said latch to assist in retaining the same in a predetermined set position.
